CRIMPING MACHINE
Ewing L. Sharp, 11032 Aqua Vista St.,
North Hollywood, Calif.
Filed Apr. 5, 1963, Ser. No. 271,030
16 Claims. (Cl. 72—306)

This invention relates to crimping machines particularly adapted to crimp electric terminals on the ends of electric wires.

Crimping machines are known in the art. The normal crimping equipment comprises a plier like device which is manually held and operated. This crimper embraces a tubular portion of a wire terminal in which the end of the wire has been inserted, and with manual force the tubular section is crushed and deformed into intimate relationship with the inserted wire. Power operated crimpers are also known, and these crimpers are of generally the same nature as the hand-operated device. They are an evolvement of the manually operated plier like device and incorporate the same type of die and operate on generally the same principle. They are simply more rigid and have power means to actuate the crimping die.

The crimping machine in the instant invention, however, is part of an entire system of packaging, handling, transporting, storing and applying wire terminals on the ends of wires. The concept of the present invention is to handle terminals in individual packages which are connected together in such a manner that each terminal is protected from damage from abrasion and is protected from dust and surrounding contamination. The packages are formed by having a series of bubbles or pockets formed in a flexible plastic sheet. A wire terminal is placed in each one of the pockets and the pockets are covered by a continuous flexible sheet. Thus each pocket or bubble is closed to prevent contamination and abrasion damage of the wire terminal enclosed in each pocket. The terminals may be packaged by automatic machinery and the package of a plurality of pockets is preferably continuous. The packaging is then rolled up on a spool for storage and transport.

The instant invention is directed to a machine for removing the terminals from the pockets, placing them in a convenient location for insertion of a wire, and crimping the terminals upon the wire.

It is thus an object of this invention to provide a machine for removing the terminals from the package and placing them sequentially in a position for insertion of the wire, and thereupon crimping the terminal over the wire.

It is another object of this invention to provide a crimping machine which automatically handles the wire terminal from package to crimping.

It is another object of this invention to provide a machine which is economic, rapid and easily operated so that it crimps terminals upon the wires with minimum cost.

It is another object of this invention to provide a handling and crimping machine which handles wire terminals from storage to crimping without causing the wire terminals to become abraded or contaminated.

Other objects and advantages of the invention will become apparent from the attached specification and drawings in which:

FIGURE 1 is a perspective view of the entire crimping machine with housing in place;

FIGURE 2 is a side elevation of the machine in FIGURE 1 taken along the line 2—2 of FIGURE 1 with the side cover removed;

FIGURE 3 is a front elevation of the machine taken along the line 3—3 of FIGURE 1 with the cover removed;

FIGURE 12 is a section taken along the line 12—12 of FIGURE 11;

20 FIGURE 13 is an enlargement of a portion of FIGURE 12;

FIGURE 14 is a schematic view of the pneumatic control circuit of this invention; and

25 FIGURE 15 is a section taken along the line 15—15 of FIGURE 12.

Referring now to the drawings, FIGURE 1 shows a perspective view of the crimping machine 10 with its covers 12 in place. The front cover 12 carries a receptacle 14 for guiding an inserted wire onto which a terminal is to be crimped. A foot controlled operator 16 is arranged at the end of a flexible control tube 18 so that it may be conveniently located next to the operator's foot. A hand controlled operator 20 is located at the front of the machine 10 convenient for manual operation.

30 A bracket 22 carries a carton 24 of tape 26. The tape 26 is stored in carton 24 and is brought to the machine in the carton. The tape 26 comprises a flat sheet on one side and a sheet secured thereto and formed with a plurality of bubbles on the other side. Each of these bubbles contains a wire terminal.

35 As is best seen in FIGURES 3, 4 and 6, the tape enters the machine and is guided into a guide 28. The guide carries the tape forward around a cylinder 30. The cylinder has substantially hemi-cylindrical grooves 32 cut axially in the circumference thereof. The grooves 32 are of such configuration as to accept the bubbles formed in the tape 26. An adjustment collar 34 is secured to the cylinder 30 and forms an edge stop for the tape 26. Its adjustability permits tapes of different widths to be used in the instant machine.

40 The cylinder 30 is mounted on a shaft 36 which is mounted in bearing 38 in swinging frame 40. A manual knob 42 on shaft 36 permits manual control of the cylinder 30. A ratchet wheel 44 is also mounted on the shaft 36. Actuation of a hereinafter described pawl advances the cylinder 30 by the amount of one groove 32 and thereby advances the tape to a new bubble.

45 Also mounted on the swinging frame 40 is an air cylinder 46. The piston rod 48 of the air cylinder 46 carries a bar 50 which in turn carries a pawl 52 which is engaged with ratchet wheel 44. One cycle of air cylinder 46, through the ratchet and pawl mechanism advances the cylinder 30 by an amount equal to the spacing between two of the hemi-cylindrical grooves 32.

50 Also mounted on the bar 50 is a forward extension 54 which is adjustably mounted thereon, and mounted on the forward extension 54 is a punch 56. Cooperating with punch 56 is a die 58. The punch and die set 56 and 58 is located adjacent the end of cylinder 30 in such a manner as to punch off a piece of the edge of tape 26 together with the associated end of an electrical connec-

tor containing bubble secured thereto. This is best seen in FIGURE 7.

The swinging frame 40 is mounted in the main frame 60 on shafts 62 and 64, see FIGURE 6. The shaft 62 carries a gear 66 with which is engaged rack 68. The rack 68 is operated by piston rod 70 of double acting air cylinder 72. The rod 70 carries a dog 74 which in turn engages a valve actuator 76 when the rod 70 is retracted into the cylinder 72. The valve actuator 76 carries a spring loaded member 78 which engages with valve 80. The valve actuator 76 itself engages the valve 82. The cylinder 72 is suitably mounted on the frame 60 and is connected pneumatically to the remainder of the system for proper control.

The shaft 64 carries a sheave 84 upon which is wound a cable 86. The lower end of cable 86 is connected to a link 88. Shaft 90 extends transversely the main frame 60 and carries a lever 92. The lower end of the lever 92 is pivoted at 94 to the link 88. The upper end of the link 88, adjacent the point where the cable 86 is attached thereto, is in the configuration of a hook. The nose 96 extends from the link 88 adjacent a recess 98 to form the hook configuration. A pin 100 is mounted in the main frame 60. When the sheave 84 rotates in a clockwise direction through the agency of air cylinder 72, the cable 86 tightens, lifts the link 88 from pin 100 and rotates the shaft 90 in a clockwise direction. When the sheave 84 thereafter rotates in counter clockwise direction, the cable 86 becomes slack. The shaft 90 is permitted to rotate in a counter clockwise direction under the control of other means until it is in a position where the recess 98 engages upon hook 100. Then the shaft 90 becomes locked in this position until the sheave 84 again rotates in a clockwise direction and removes the link 88 from locking engagement with pin 100.

The shaft 90 carries a head 102 thereupon. The head is rotatable under the control of shaft 90 and aperture 104 extends through the head 102 and several operative elements extend into the aperture upon actuation of the operative elements. A T-slide in the head 102 carries a sliding stop 106. A cam face 108, when engaged with an appropriate cam 110 thrusts a stop-finger 112, mounted on stop 106 in front of the aperture 104. A spring 114 retracts the stop 106 and stop finger 112 when the cam face 108 is not in contact with cam 110.

Mounted on the side of the head 102 away from the stop 106 is a circular boss 116. The boss 116 is slotted at 118 to carry a plurality of sliding clamp members 120. The clamp members have jaws 122 which co-act together to clamp an electrical connector, when located therebetween. The clamp members are urged inwardly by means of a garter spring 124 and each clamp member 120 carries a pin 126 in engagement with a clamp member retracting means. The retracting means comprises a substantially square clamp operator 128 rotatably mounted on circular boss 116. The clamp operator 128 carries a nose 130 which is engaged by a slide 132 which is T-slot mounted in the head 102. The slide 132 carries a cam face 134 which engages with a cam 136 for operation thereby. When the cam 136 operates slider 132, the clamp operator 128 is rotated in such a direction as to open the jaws of 122. A spring 138 connected between the head 102 and a pin 140 on the cam operator 128, urges the cam operator 128 in such a direction as to permit the garter spring 124 to close the jaws 122. A funnel 142 is mounted on boss 116 co-axially with aperture 104 to guide electrical connectors therein. The funnel 142 also acts as a flange member to hold the clamp operator 128 in position.

Also mounted in the head 102 are crimping means arranged to crimp an electrical connector over a wire terminal clamped therein. These crimping means comprise crimping dies of suitable nose configuration for the purpose intended, mounted in radial holes 146 in crimping die holder 148. The holes 146 are of two different

diameters, with a smaller diameter near the nose of the crimping dies 144 to serve as guide therefor, and the larger diameter to guide the head 152 of the crimping dies 144. The space between serves as a pocket for springs 150 which cause retraction of the crimping dies 144. The construction is best seen in FIGURES 11 and 12.

Surrounding the crimping die holder 148 is a die operator 156 which contains internal cam faces 158 which engage upon the end of the crimping dies 144 away from the crimping die noses. Rotation of die operator 156 is accomplished by a lever 160. Upon clockwise rotation of lever 160 the cam faces 158 act upon the crimping dies 144 to close them and cause crimping.

While four clamp members 120 and four crimping dies 144 are shown, it is obvious that any desirable number can be employed. In some cases three clamps and three crimping dies will be satisfactory, but in general it is felt that three or more of such clamps and dies would be desirable.

Clockwise rotation of die operator 156 and lever 160 is caused by the extension of piston rod 162 from cylinder 164. Counter clockwise operation of lever 160 and die operator 156 is accomplished by a spring 166 and causes opening of the crimping dies 144. The limit of opening of the crimping dies 144 is established by an adjustable stop screw 168 mounted in head 102. Clockwise operation in the crimping direction is limited by an adjustable stop 170 located in the path of travel of lever 160. The cylinder 164 is single acting, with air pressure in the top of the cylinder causing the rod 162 to extend, and the cylinder 164 contains a spring 172 which causes retraction of the rod 162. The rod 162 carries an adjustable actuating collar 174, see FIGURE 9, which engages with a valve actuator 176 which is pivoted at 178. The valve actuator 176 is arranged in such a manner as to swing in a counter clockwise direction around pivot 178 when the piston rod and adjustable actuating collar 174 are moving in a downward direction. This does not cause actuation of the valve 180. However, retraction of the piston rod 162, carrying adjustable actuating collar 174, causes engagement of the valve actuator 176 to cause clockwise motion thereof around pivot 178 and cause actuation of the valve 180.

As best seen in FIGURE 4, the head 102 has two operative positions. The rotation in the clockwise direction, as viewed in this figure, is under the control of shaft 90 which in turn is controlled by sheave 84. A dash pot 182 is mounted on the main frame 60 adjacent the clockwise position of head 102. A cam lever 184 is pivoted at 186, near the bottom of cam lever 184, to the main frame 60. Cam lever 184 is in engagement with the operating piston rod 188 of the dash pot 182, and its cam face is adapted for engagement with the edge of the head 102. The dash pot is arranged in such a manner that motion of the rod 188 into the dash pot, in the leftward direction of FIGURE 4, is limited in speed by the flow of air or oil through an orifice in the dash pot. The cam face of cam lever 184 is of such configuration so as to cause motion of the rod 188 into the dash pot when the head 102 is moving in a counter clockwise direction from its most clockwise position, as shown in dotted lines in FIGURE 4. Gravity acting on head 102 causes its descent which is slowed by dash pot 182 in the manner previously described. The gravity motion of head 102 may be aided by means of a spring (not shown).

Referring now to the schematic circuit of FIG. 14, an air supply source is seen at 190. This source delivers air to a conventional pressure regulator 192 which may be followed by a lubricator, if desired, not shown. Air under pressure is thus delivered to line 194 which in turn supplies air under pressure to lines 196, 198 and 200. Branching from line 200 is line 202 which supplies air under pressure to foot controlled operator 16. The operator 16 is simply a shut-off valve which is spring

urged in the off position and in this position the foot pedal 204 is in the upward, nonactuated position. Upon depression of the foot pedal 204, air under pressure is supplied from line 202 to line 18. Connected to line 18 is a cylinder 206 containing plunger 208. When pressure is applied to line 18, the plunger 208 moves to the left as seen in FIG. 14. Lever 210 is operatively connected to plunger 208 so that it is actuated thereby. Lever 210 is pivoted at 212 and is also connected to the hand controlled operator 20. When the plunger 208 is actuated to the left, its connection through lever 210 causes motion of valve stem 214 to the right. Valve stem 214 is located in valve body 216 and line 196 is connected to supply air under pressure to the valve body 216. Valve stem 214 carries lands of such configuration, that when operating in conjunction with ports in valve body 216 air is permitted to flow from line 196 to line 218 when the stem 214 is in its right-hand, operative position. When the stem 214 is in its left-hand, non-operative position, line 196 is cut off from communication with line 218. Stem 214 also carries a piston on its right-hand end in such a manner that air on the right-hand end of this piston causes leftward motion of the valve stem 214. Line 220 is connected to line 218 and contains therein a check valve-orifice structure 222 which is in turn connected to the right-hand side of the piston on stem 214. Check valve-orifice structure 222 is of conventional nature and is of such type that air flow to the right through this structure is unrestricted, while air flow to the left is controlled by the orifice therein.

Thus it can be seen that actuation of either foot controlled operator 16 or hand controlled operator 20 causes air pressure to be communicated to line 220. However, the piston on valve stem 214 causes the air pressure to be disconnected after a short period depending upon the orifice in the check valve-orifice structure 222. This surge of pressure in line 220 is communicated by that line to the space above piston 224 mounted on piston rod 162. When such surge occurs the piston 224 is urged downwardly against spring 172 and carries with it the piston rod 162, which causes crimping as is hereinbefore described. When the pressure is cut off of line 220 by action of valve stem 214, under control of orifice in structure 222, the spring 172 urges the piston 224 in the upward direction. A vent 226 appropriately located in the side of cylinder 164 permits the air above piston 224 to escape. During rise of the piston, the collar 174 causes actuation of valve 180. This has an effect which is hereinafter described.

Valve body 228 of valve 230 contains a pressure port connected to air pressure line 198. The body also contains a spool 232 which carries lands 234 and 236. Lines 238 and 240 are connected to ports in the valve body 228 in such a manner as to be controlled by the lands 234 and 236 on spool 232, and are connected to opposite ends of cylinder 72. When the spool 232 is in its right-hand position it permits air under pressure to pass from air supply line 198 to line 240, and in this position the line 238 is either connected to vent to atmosphere or contains a leak to atmosphere at 242. An orifice leak of this nature is also located in line 240 at 244. Lands 234 and 236 contain axial orifice holes therethrough so that air pressure communicated to the center portion of the spool 232 from line 198 is also communicated to the left of land 234 and to the right of land 236.

Accordingly when the collar 174 actuates valve 180, line 246 connected to the space at the left-hand of land 234 is vented to atmosphere through valve 180. Spool 234 then passes to the left through the agency of air pressure passing from the center of the spool to its right-hand end through the orifice in land 236 thus causing the spool 234 to close communication of air pressure from line 198 to line 240 and open communication from

line 198 to line 238. Pressure in line 238 passes into the double acting air cylinder 72 and retract the piston rod 70 with attached rack 68. Air on the other side of the piston in cylinder 72 bleeds out of the orifice 244. 5 Motion of dog 74 on the piston rod 70 causes it to engage the valve actuator 76. Spring loaded member 78 actuates valve 80 which permits communication of pressure from line 200 to line 248. A check valve-orifice structure 250 in line 248 causes metering of the air in the direction toward air cylinder 46. When the spring loaded member 78 is not actuating valve 80, line 248 is connected to atmosphere and check valve-orifice structure 250 permits unrestricted flow of air from the cylinder 46 to atmosphere through valve 80. Spring 252 returns the piston rod 48 into the cylinder 46.

Further actuation by retraction of piston rod 70 causes valve actuator 76 to engage and actuate valve 82. Valve 82 is connected by line 254 to the right-hand side of land 236 and actuation of valve 82 causes venting of line 254 and the space to the right of land 236 to the atmosphere. When this occurs the spool 232 again shifts to the right. The shifting causes pressurization of line 240 from line 198, and accordingly extends the piston rod 70 from cylinder 72 to return the entire mechanism to the position shown in the FIG. 14.

The operation of this equipment has been described in part, but a complete cycle of operation is described below. Assuming that the machine has been in operation for some time, and the operator is ready to place another wire into the machine for crimping of a terminal thereon, the machine has its swinging frame 40 in the position shown in FIG. 4 with the piston rod 70 extended as shown in FIG. 2. This situation is also shown in FIG. 14. In this condition the terminal is clamped in proper location between the jaws 122 and the operator thrusts a stripped wire into the hollow end of the terminal. This operation may be aided by a guide 256 so that the wire goes easily into the hollow end of the terminal. Thereupon the operator depresses foot pedal 204 or hand control operator 20. This action permits air pressure to be communicated from line 196 to line 220 and extends the piston rod 162. As seen in FIG. 3 the rod 162 engages with the lever 160 and causes actuation of the crimping dies 144. The hollow end of the terminal is crimped around the wire in a very secure, electrically conductive fashion. Very shortly after crimping the communication between air pressure line 196 to line 220 is terminated and the piston rod 162 is retracted into cylinder 164 by agency of spring 172. Crimping has been completed.

When the collar 174 on piston rod 162 actuates valve 180, the line 246 is exhausted and spool 232 moves to the left. Thereupon air pressure is communicated from line 198 to line 238 urging the piston rod 70 into the cylinder 72. This rotates the swinging frame 40 in a clockwise direction as viewed in FIGURE 2 into a position where the cylinder 46 extends to the right as viewed in FIGURE 2. This position is seen in FIGURE 7. This rotation tightens cable 86 and lifts the hook off of pin 100. Continued rotation of sheave 84 pulls the link 88 and causes the head 102 to rotate from its vertical position, as shown in FIGURE 2, about the axis of shaft 90 until it is in a horizontal position. When moving to the horizontal position the head, carrying stop 106 and slide 132, causes engagement of the cam face 108 with cam 110 to thrust the stop finger 112 in front of the aperture 104. Substantially concurrently therewith, the cam face 134 engages with cam 136 to cause opening of the clamp jaws 122 and release of the jaws from clamping position. The clamping force of the jaws 122 is such that the operator has previously pulled the connector out of engagement with the jaws 122 by pulling the wire out of aperture 104. As the head 102 goes up into horizontal position, it engages the cam lever 184 so that the upper

face of cam lever 184 supports the head 102 against rapid downward movement.

Retraction of the piston rod 70, which causes this rotation of swinging frame 40, also causes the dog 74 to engage with the valve actuator 76 and causes actuation of valve 80. Thus air is supplied from line 200 to line 248 and cylinder 46 is actuated. The piston rod 48 is extended and through the agency of pawl 52 engaging the ratchet wheel 44, the cylinder 30 indexed to a new hemi-cylindrical groove 32.

An appropriate tape having bubbles corresponding to the hemi-cylindrical grooves 32 has previously been inserted through guide 28 and is controlled by the grooves 32 of the cylinder 30. A suitable wire connector or terminals is packaged in each one of the bubbles in the tape 26 and these connectors are sufficiently loose in the bubbles to fall to the downward end of the bubble by gravity. Extension of the piston rod 48 also moves the punch 56 into the die 58 and punches off the top of the bubble. Further retraction of the piston rod 70 into the cylinder 72 actuates valve 82 to open line 284 to vent the atmosphere, and the spool 232 shifts to the right as shown in FIGURE 14. In this position of the spool 232 air is supplied from pressure line 198 to line 240 and the piston rod 70 is again extended. Such extension rotates the swing frame 40 in a counter clockwise direction as shown in FIGURE 2 until the cylinder bottoms in the position shown in FIGURE 2. This motion of the piston rod 70 disengages dogs 74 from valve actuator 76 and valve 80 thus line 248 is vented to atmosphere. This happens concurrently with the swinging of the frame 40, and the wire connector in the bubble that has just had its top punched off drops through guide 258 into funnel 142, through aperture 104 until it hits stop finger 112. While cable 86 is slack in this condition, the cam lever 184 with its dash pot 182 prevents rapid downward motion of the head 102. The head stays in the horizontal position in FIGURE 4 until the connector drops into the aperture against the stop 112 as described. The descent of head 102 is timed so that the head drops after the connector is located therein. In dropping, the head 102 rotates around the pivot of shaft 90 in a counter clockwise direction as viewed in FIGURE 4 and the cam face 134 leaves cam 136 to permit the jaws 122 to clamp the connector in the proper position. Thereafter the stop finger 112 is retracted and the head 102 swings into the vertical position shown in FIGURE 4. It is latched in this position by having the recess 98 in link 88 hook on pin 100. Now the machine is in a condition for a further actuation. The operator again thrusts a wire into the hollow end of the new connector and operates the hand or the foot controlled operator, thereby causing the machine to go into another cycle as hereinbefore described.

When one tape 26 runs out, another one can be inserted in the guide 28 and the cylinder 30 rotated by means of manual knob 42 until the first bubble therein is located in operative position. Exhausted tape, having its wire terminals removed therefrom is guided out of the machine through a guide 258 for disposal as waste. If the new tape is of different width than the prior tape, because the connectors contained therein are of a different length, the collar 34, which engages one edge of the tape 26, is adjusted so that the opposite edge of the tape is adjacent the punch-die combination 56 and 58.

Having pointed out the preferred embodiment of this invention, it is obvious to those skilled in the art that numerous embodiments and modifications within the skill of routine engineering are possible. Accordingly, it is requested that this invention be defined by the scope of the appended claims.

I claim:

1. In a machine for operating upon wire connectors packaged one connector to a bubble in a continuous strip

with the wire connectors loose within the bubble, the invention comprising:

swingable frame means rotatable from a first position to a second position, punch means mounted upon said frame means and arranged to punch off one end of the bubble when said frame is in its first position, the wire connector falling from the bubble when said frame means is moved to said second position;

head means to operate upon the wire connector, said head means being positioned in association with said frame means so as to receive the connector falling from the bubble, said head means including means to locate the wire connector, means to clamp the wire connector and means to crimp the wire connector so that the wire connector is removed from its package and crimped upon a wire in one continuous automatic operation.

2. The structure of claim 1 wherein said swinging frame is connected to said means to punch off the end of the bubble to actuate said means to punch off the end of the bubble.

3. The structure of claim 1 wherein said means to crimp is connected to said swinging frame means to rotate said swinging frame means.

4. The structure of claim 1 further including advancing means mounted on said frame means connected to advance a new connector containing package into operative position.

5. In a machine for operating upon wire connectors packaged loosely in individual packages along a length of tape, the improvement comprising:

means to control the tape and advance it from one position to another position in succession, swinging frame means swinging from a first to a second position, said swinging frame means carrying said means to control and advance the tape, said swinging frame means carrying punch means to cut off the end of one of the packages while the connector is held in the other end thereof, means connected to said frame means to swing said swinging frame means from said first to said second position so that the connector falls out of the open end of the package, means adjacent the cut end of the package to guide the connector into a position where it is accessible, means at the accessible position to stop the connector when it reaches the accessible position, means at the accessible position to restrain the connector in the accessible position, and means at the accessible position to crimp the connector on a wire while it is in said accessible position.

6. The structure of claim 5 wherein said means to swing said frame from said first position to said second position is connected to said guide means to control said guide means.

7. The structure of claim 5 further including a power means, said punch means and said tape advancing means being connected to said power means to be operated by said power means.

8. The structure of claim 5 wherein said power means is air actuated means.

9. In a machine for operating upon parts individually packaged in a plurality of packages associated together on a tape, the improvement comprising:

a swinging frame pivoted to move from a first position to a second position, means connected to said swinging frame to move said swinging frame from said first position to said second position and back to said first position, tape control means mounted on said swinging frame, said tape control means advancing the tape serially from one position to a next position, package opening means mounted on said swinging frame and arranged to open a package when said swinging frame is in its first position; guide means associated with said swinging frame, said

9

guide means guiding the part falling out of the open package when said swinging frame is in its second position, said guide means guiding the part to a position where it may be operated upon.

10. The structure of claim 9 wherein the package opening means is connected to said tape control means to cause advance of the tape packages from one position to the next upon the operation thereof.

11. The structure of claim 9 wherein said package control means comprises a cylinder rotatably mounted on said frame, said cylinder having grooves corresponding to each package, power means connected to said cylinder to rotatably advance said cylinder upon each package opening operation to serially bring new packages into position to be opened.

12. The structure of claim 9 wherein the parts are guided into a head mounted adjacent said swinging frame, means on said head to stop the parts in position and means on said head for clamping the parts in position.

13. The structure of claim 12 further including means in said head to operate on the part when it is clamped into position, said means to operate being crimping dies to crimp the part.

14. In a machine arranged to operate upon wire connectors individually packaged in loose packages serially connected together by tape, the improvement comprising:

a swinging frame movable from a first position to second position and back to the first position, a cylinder mounted on said swinging frame, said cylinder having axially aligned grooves corresponding to the packages, means to advance said cylinder from one groove to another so that the packages may be serially operated upon, package opening means comprising a punch and die to punch off the end of a package while said swinging frame is in its first

position, power means to advance said cylinder and to open said package;

an operating head having a first position and a second position, said operating head being moved into its first position by motion of said swinging frame into its first position, said operating head moving into its second position upon motion of said swinging frame into its second position;

guide means on said swinging frame for guiding the part as it falls from its package when said swinging frame moves to its second position, said guide means guiding said part into the operating head when said operating head is in its first position, said operating head thereafter moving into its second position, stop means mounted in said operating head locating said part in said operating head, clamp means in said operating head operating to clamp said part as said operating head moves from its first position to its second position and means in said operating head to operate on the part when said operating head is in its second position.

15. The structure of claim 14 wherein said operating means is means to crimp the part upon a wire.

16. The structure of claim 14 wherein power means is connected to said swinging frame to rotate said swinging frame from said first position to said second position and power means is connected to operate said operating means to actuate said operating means to operate on the part.
